Primary Examiner—Dominic Simone(74) *Attorney, Agent, or Firm*—Marshall A. Lerner; Marvin H. Kleinberg; Klein & Lerner, LLP(57) **CLAIM**

The ornamental design for a periphery of an outsole, as shown and described.

DESCRIPTION

FIG. 1 is a perspective view of a first exemplary embodiment of a periphery of an outsole in accordance with my new design.

FIG. 2 is a left side view thereof;

FIG. 3 is a right side view thereof;

FIG. 4 is a top plan view thereof;

FIG. 5 is a rear elevation view thereof; and,

FIG. 6 is a front elevation view thereof.

Broken lines in the figures are for illustrative purposes only and form no part of the claimed invention.
